HUMIDIFIER

Filed Feb. 13, 1922

UNITED STATES PATENT OFFICE.

CHARLES E. HENDRIX, OF JEFFERSON CITY, MISSOURI.

HUMIDIFIER.

Application filed February 13, 1922. Serial No. 536,051.

To all whom it may concern:

Be it known that I, CHARLES E. HENDRIX, a citizen of the United States of America, a resident of Jefferson City, county of Cole, State of Missouri, have invented certain new and useful Improvements in Humidifiers, of which the following is a full, clear, and exact description, reference being had to the accompanying drawing, forming 10 a part of this application.

This invention relates to improvements in humidifiers and has for its object the production of a simple and inexpensive device which may be used in connection with a 15 furnace, stove or other heating medium, whereby the heated air arising from said heating medium is provided with moisture.

A very serious objection to the use of hot air as a means of heating the rooms of houses 20 results from the fact that the air, which is passed through or over the heating medium, is unduly dried and thereby deprived of certain of its natural elements, thus affecting the healthful condition of the rooms into 25 which said heated air is directed.

In the use of the device disclosed herein, the air, after being heated, passes in close proximity to a body of water, and by being commingled with the vapor arising from 30 said water is again supplied with the natural elements of which it was deprived by being brought into contact with the heat-producing element.

Another object is to produce a device of 35 the kind disclosed herein, which includes automatic controlling means whereby the supply of water to said device is regulated, thus providing a means for maintaining, at all times, a predetermined amount of water in the receptacle provided for that purpose.

With the foregoing and other objects in view, the invention comprises the novel construction, combination and arrangement of parts hereinafter more specifically described 45 and illustrated in the accompanying drawing wherein is shown the preferred embodiment of the invention. However, it is to be understood that the invention comprehends changes, variations and modifications which 50 come within the scope of the claims hereto- unto appended.

Fig. I is a side elevation of a furnace of the hot air type, with the humidifier in place 55 therein, a part of said furnace being broken

Fig. II is a plan view of the humidifier with the deflectors removed.

Fig. III is a longitudinal section through the humidifier, a portion of the pipe connecting the evaporation receptacle and the 60 supply receptacle being shown in elevation.

Fig. IV is an inverted plan view of the deflectors.

Fig. V is an enlarged cross section through the liquid-conducting member and the spirally bent wire which supports same. 65

Fig. VI is an enlarged sectional detail of fragments of the deflectors showing the manner of connecting said deflectors together.

Fig. VII is an enlarged sectional detail 70 of fragments of the deflectors showing the manner of supporting said deflectors on the evaporation receptacle.

In the drawing, A designates a furnace 75 preferably of the hot-air type which is provided with the usual fire-pot B. In this type of furnace cold air is drawn into said furnace at a point close to the bottom thereof, said air then moving along said fire-pot B whereby it is heated, after which said air 80 is conducted to the room or rooms which it is desired to heat.

Supported in any suitable manner by the furnace A at a point adjacent to the upper portion thereof is my improved humidifier 85 H, which comprises an evaporation receptacle 1 located within the furnace, preferably at a point immediately above the fire-pot B and directly in the path of the upwardly moving current of heated air, and a 90 supply receptacle 2, said evaporation receptacle 1 and said supply receptacle 2 being in communication with each other through the use of a pipe 3, whereby liquid placed in the supply receptacle 2 is conducted to the 95 evaporation receptacle 1.

The supply receptacle 2 is intended as a reservoir for the water to be conducted to the evaporation receptacle, and in towns and cities which are provided with water under 100 pressure, a pipe 4 will connect said supply receptacle 2 with the city water system whereby water will be conducted to said supply receptacle without manual effort on the part of any of the occupants of the house in 105 which the furnace is located. To automatically regulate the amount of water delivered to the supply receptacle 2 and to maintain at all times a predetermined amount of water therein, I employ a valve 5 which is secured 110

to the end of the pipe 4 within the supply receptacle 2, the opening and closing of said valve being controlled by a float 6 supported by the water within the receptacle 2. The 5 float 6 is fixed to one end of an operating arm 7, the opposite end of said arm being secured to the stem of the valve 5. Thus it is apparent that when the water level within the supply receptacle 2 falls, due to evaporation 10 of some of the water in the evaporation receptacle 1, said float 6 will drop, thereby opening the valve 5 and permitting water to flow into said supply receptacle through the pipe 4, and when said water has again 15 reached its proper level in said supply receptacle, the valve 5 will be closed by the corresponding rise of the float 6.

The evaporation receptacle 1 and the supply receptacle 2 are located in the same 20 horizontal plane, and because said receptacles are in direct communication with each other, through the use of the pipe 3, water will flow from the supply receptacle to the evaporation receptacle and said water will 25 attain corresponding levels in both receptacles.

To provide a means for causing the water within the evaporation receptacle 1 to rise therein, so that the same will be brought 30 more directly into the path of the heated air, I employ a moisture-conducting member C, comprising a spirally arranged wire 8 which is enveloped by an absorbent member 9, said member 9 being of tubular shape 35 in cross section, and its edges being secured together by means of stitches 10 (Fig. V). The absorbent member 9 envelops the spiral wire 8 throughout its length, and an end 9' of said absorbent member extends downwardly from the outer end of said spiral wire 8, which downwardly extending end is submerged in the water within the evaporation receptacle, and because of the submerged end 9' the water within the receptacle will rise by capillary attraction and 40 saturate all of the spirally arranged portion of said moisture-conducting member 9.

The spirally arranged portion of the moisture-conducting member C is located 50 adjacent to the upper edge of the evaporation receptacle 1, said spiral portion being retained in that particular position by means of a plurality of floats 11 which may be formed of cork or other buoyant material, said floats being supported by the water in the receptacle 1. The moisture-conducting member C is secured to the floats 11 by any suitable means, such, for instance, as staples 11' (Fig. II), the legs of said staples straddling portions of said member C and being driven into said floats 11, whereby said member C is secured to said floats 11.

To cause the heated air which passes in close proximity to the evaporation receptacle 1 to be directed against the moisture-

conducting member 9, I provide said evaporation receptacle 1 with deflectors 12 and 13. The deflector 12 comprises an upwardly inclined annular band, which extends outwardly beyond the circumferential wall of 70 the receptacle 1 (Fig. III), and is provided with a downwardly curved portion 12' at its inner edge. To provide a means for supporting the deflector 12 on the evaporation receptacle 1, I provide said deflector 12 with 75 a plurality of supporting members 14, said supporting members being secured to said deflector by means of solder or similar means, and each being provided with a curved lower end portion adapted to engage 80 the upper edge of the receptacle 1 (Fig. VII). The deflector 13 is located above the opening 15 in the deflector 12 and comprises an imperforate concave member supported by the deflector 12 by means of a plurality of 85 supporting members 16, one end of each of which is soldered to the deflector 12 and the other end of each of said supporting members being soldered to the deflector 13.

The operation of my device is as follows: 90

Assuming that the evaporation receptacle 1 contains water which has been placed and maintained therein in the manner hereinbefore described, said water will saturate the moisture-conducting member C from end to 95 end by being compelled to move therealong through capillary attraction, and because of the spirally arranged portion of said moisture-conducting member a comparatively wide moistened area will be presented. The heat of the furnace will cause vapor to rise 100 from the water in the receptacle 1 and from the saturated member C, and as the upwardly moving current of heated air comes into contact with the deflector 12, said air will be directed inwardly by the inclination of said deflector 12 and downwardly into 105 said receptacle 1, by the curved portion 12' thereof, and will there commingle with said vapor, after which it will pass through the opening 15 in the deflector and be deflected outwardly by the deflector 13, and be conducted to the rooms it is desired to heat. 110

I claim:

1. A humidifier comprising an evaporation receptacle, said evaporation receptacle being adapted to contain liquid, buoyant means supported by said liquid, and absorbent means within said receptacle, said absorbent means being supported by said 115 buoyant means and being in contact with the liquid within said receptacle whereby said liquid is caused to travel along said absorbent means.

2. A humidifier comprising an evaporation receptacle, said evaporation receptacle being adapted to contain liquid, and absorbent means spirally arranged within said receptacle, a portion of said absorbent means being in contact with said liquid to cause 120 125 130

said liquid to travel along said absorbent means.

3. A humidifier comprising an evaporation receptacle, said evaporation receptacle being adapted to contain liquid, and an absorbent means along which said liquid travels, said means comprising a spirally arranged portion located adjacent to the upper edge of said receptacle and a downwardly extending portion submerged in the liquid in said receptacle.

4. A humidifier comprising an evaporation receptacle, said evaporation receptacle being adapted to contain liquid, buoyant means supported by said liquid, and an absorbent means supported by said buoyant means, said absorbent means comprising a spirally arranged portion located adjacent to the upper edge of said receptacle and a downwardly extending portion submerged in the liquid within said receptacle.

5. A humidifier comprising an evaporation receptacle, said evaporation receptacle being adapted to contain liquid, and an absorbent means along which said liquid travels, said means comprising a spirally arranged portion located adjacent to the upper edge of said receptacle and a downwardly extending portion submerged in the liquid within said receptacle, said last mentioned means being provided with a plurality of floats which are supported by the liquid within the receptacle.

6. A humidifier comprising an evaporation receptacle, said evaporation receptacle being adapted to contain liquid, and means for causing said liquid to rise by capillary attraction toward the upper edge of said receptacle, said means comprising a spirally bent wire located adjacent to the upper edge of said receptacle, a fabric liquid-conduct-

ing member enveloping said spirally bent wire, one end of said liquid-conducting member being submerged in the liquid within said receptacle and floats supported by said liquid upon which said liquid conducting means rests.

7. A humidifier comprising an evaporation receptacle, adapted to receive a current of heated air, said evaporation receptacle being adapted to contain liquid, absorbent means within said receptacle along which said liquid travels and deflectors supported by said evaporation receptacle at the upper edge thereof and arranged one above the other, whereby said heated air is caused to pass in close proximity to said absorbent means.

8. A humidifier comprising an evaporation receptacle adapted to receive a current of heated air, said evaporation receptacle being adapted to contain liquid, means for causing said liquid to rise by capillary attraction toward the upper edge of said receptacle, said means comprising a spirally bent wire located adjacent to the upper edge of said receptacle, a fabric liquid-conducting member enveloping said spirally bent wire, one end of said liquid-conducting member being submerged in the liquid within said receptacle and floats whereby said means is supported, deflectors whereby said heated air is caused to pass in close proximity to said liquid-conducting member, a supply receptacle, and means including a float-controlled valve located within said supply receptacle whereby the amount of liquid permitted to pass therefrom to first mentioned receptacle is regulated.

In testimony that I claim the foregoing I hereunto affix my signature.

CHARLES E. HENDRIX.
